UNITED STATES PATENT OFFICE.

ALBERT H. STEBBINS, OF LOS ANGELES, CALIFORNIA.

OPERATING MEANS.

Application filed February 6, 1926. Serial No. 86,533.

This invention relates to novel means for imparting a progressive vibratory movement to concentrator decks, screens and other frames supported for vibratory movement.

5 The proper operation of table concentrators depends largely upon the nature of the movement employed, for while the vibratory movement should serve to advance the materials over the deck surface, it should not be sufficiently energetic to interfere with the stratifying operation of the materials. The nature of the movement imparted to screens and other separating devices is likewise important for, while it should agitate the materials to promote their separation, it should not be sufficiently energetic to hurry the materials along without properly separating them.

Although various forms of operating 20 means have been proposed heretofore, difficulty has been experienced in developing a simple construction that could be readily adjusted to produce the desired operating movement, and which is capable of being 25 operated with a minimum amount of power.

The present invention is therefore directed to a simple form of operating means that may be readily adjusted to produce any desired type of movement, and which is 30 strong and durable and requires only a relatively small amount of power to impart a quick initial movement to a heavy deck, screen or other device being vibrated.

One important feature of the present invention resides in a rocking member having 35 a cable actuating portion that is off-set from the axis about which the rocking member rotates, and in means for rocking the member to thereby alternately tension and slack 40 off the operating cable.

Another feature of the invention resides in an operating cable having one end anchored and its other end connected to the frame to be actuated while an intermediate 45 portion of the cable is looped about an actuating element in such a manner that the movement imparted to the frame by the cable is twice as great as the movement of the actuating element.

50 Another feature of the invention resides in the construction whereby the nature of the movement imparted to the device being operated may be varied as desired by changing the position of the angle through which the rocking member oscillates.

55 Still another feature of the invention re-

sides in the arrangement of the cable or cables whereby a minimum amount of power will suffice to operate the mechanism, and whereby the wear and tear upon the operating parts is reduced to a minimum.

60 Other features of the invention and novel combination of parts in addition to the above will be hereinafter described in connection with the accompanying drawings which 65 illustrate good practical forms of the invention.

In the drawings:—

Figure 1 is a side elevation with parts in 70 section of a frame supported for vibratory movement and shows operating means constructed in accordance with the present invention;

Figure 2 is a plan view of the supporting 75 base and operating means of Fig. 1, the vibratory frame being indicated in dotted lines;

Fig. 3 is a sectional view taken on the line 3—3 of Fig. 1;

Fig. 4 is a side view of Fig. 3;

Fig. 5 is a side view of a frame supporting 80 base showing a modified form of operating means;

Fig. 6 is a view similar to Fig. 5, but shows a second modified form of operating 85 means;

Fig. 7 is a sectional view taken on the line 7—7 of Fig. 6; and

Fig. 8 is a diagrammatic view showing the 90 operating mechanism of Fig. 1 on an enlarged scale.

The operating means of the present invention is well adapted to impart a progressive vibratory movement to concentrator decks, screens and various other devices supported for back and forth movement.

95 Referring to Figs. 1 and 2 of the drawings the frame 10 may constitute the supporting carriage for a concentrator deck or screen, or other structure mounted for back and forth movement. The casing shown for supporting the frame 10 is provided with the longitudinally extending side rails 11 which are secured to the uprights 12, and in the present case the means shown for supporting 100 the frame 10 upon its casing consists of the transversely extending shafts 13 which are supported near the opposite ends of the base or casing by the brackets 14. These shafts are provided at their opposite ends with the 105 downwardly extending arms 15 having adjacent their lower ends the laterally extend-

ing stub shafts 16 that extend into bearing blocks 17 secured to the under face of the frame 10. The arrangement is such that this frame will partake of a slight rising and falling movement as it moves back and forth in the direction of its length. The construction so far described forms no essential part of the present invention and may be varied as desired.

10 The operating means forming the subject matter of the present invention may be variously constructed and a good, practical form is shown in Figs 1 to 4 inclusive which will now be described. The frame 10 is shown as provided with yielding means for urging the same in a right hand direction viewing Fig. 1, and with power operated means for moving the frame in the left-hand direction. The yielding means illustrated 15 consists of a cable 18, one end of which is secured to a threaded pipe or bar 19 which is adjustably secured to the frame 10, while the opposite end of the cable 18 is secured to a threaded tube or bar 20 having adjustable nuts 21 at its outer end, and a coiled spring 22 is confined between these nuts and a transversely extending bar 23 of the supporting casing.

An intermediate portion of the cable 18 30 passes around a grooved pulley or sheave 24 which is rotatably supported by a shaft 25. The ends of this shaft are mounted in the brackets 26 secured to the longitudinally extending beams 27 that may be fastened to 35 the upper portion of the supporting casing so that they lie parallel to and between the spaced side rails 11 of the supporting casing. In the construction just described the tension of the spring 22 may be varied as 40 desired by adjusting the nuts 21 so that the cable 18 will exert a continuous pull upon the frame 10 urging the same in a right-hand direction with the desired amount of force.

45 The power operated means for moving the frame 10 in the left-hand direction consists of a cable 28 one end of which is secured to the threaded tube or rod 29 fastened to the frame 10. This cable is shown as 50 extending around a grooved sheave or pulley 30 supported by the shaft 31 the opposite ends of which are mounted in the brackets 32, and the cable passes downwardly from the sheave 30 to the means which serves to 55 tension and slack off the cable. This means might be variously constructed and as shown in Figs. 1 and 2 comprises the grooved sheave 33 which is supported for movement bodily towards and from the upper sheave 30, and the means shown for supporting and imparting cable operating movement to the sheave 33 consists of a crank shaft 34 journaled in bearing brackets 35 secured to the side beams 11 of the supporting casing. 60 This crank shaft has an offset portion or

wrist-pin 36 upon which the sheave 33 is journaled, and the sheave is preferably split as will be apparent from Fig. 3 so that the opposite halves of the sheave may be fastened about the wrist pin by the bolts 37. 70 The arrangement is such that rocking movement of the crank shaft 34 moves the sheave 33 bodily toward and from the sheave 30.

In practice it is found desirable to rock the crank shaft 34 through a relatively 75 small angle to actuate the sheaves 33. It is therefore desirable to provide means for increasing the movement imparted to the frame 10 by the cable 28 so that movement of the sheave 33 through a small angle will 80 impart the desired amount of movement to the frame 10. In accordance with the present invention this is accomplished by looping an intermediate portion of the cable 28 about the sheave 33 and by anchoring one 85 end of the cable to the supporting casing. The end portion of the cable 28 that extends upwardly from the lower sheave 33 is therefore provided with anchoring means which consists of an eye or yoke 38 that is 90 pivotally mounted upon the transversely extending shaft 39.

As a result of this construction the movement imparted to the portion of the cable 28 that is secured to the frame 10 will be 95 double the movement imparted to the sheave 33 in the cable tightening direction. In this manner a relatively slight movement of the sheave 33 will suffice to impart the desired amount of movement to the frame 10. 100

The arc through which the wrist pin 36 of the crank shaft is rocked to actuate the sheave 33 may assume various positions about the axis of the shaft 34, but this arc preferably lies either at the upper or lower side of the shaft 34 so that the sheave 33 during part of its movement will travel in approximately a horizontal direction as will hereinafter more fully appear.

The power operating cable 28 and the actuating sheave for this cable are shown in Fig. 1 in full lines in the position they occupy when the frame 10 has reached the end of its stroke in the right hand direction, and in dotted lines in the position they occupy when the frame 10 has reached the end of its stroke in the left-hand direction. It will therefore be apparent from the two positions of these parts that the crank shaft 34 rocks through a relatively small angle in imparting the back and forth movement to the frame 10, and it should be noted that when the frame 10 is moved to the left-hand end of its path of travel the wrist pin 36 of the crank shaft occupies a position in which it lies at its greatest distance from the upper sheave 30. As a result of this arrangement the movement of the crank shaft in the cable let-off direction will be such that it will slack off the cable with a slow initial movement 110 115 120 125 130

that gradually increases as the angle through which the wrist pin moves changes. In other words the operating parts are so constructed that the off-set portion of the crank 5 shaft 34 is rocked back and forth through a small angle (say less than 40°) lying adjacent the dead centre position of the wrist pin 36 with respect to the cable 28. The speed at which the frame 10 is moved by the 10 cable 28 rapidly decreases as the parts approach the dead centre or zero position in which they are shown in full lines in Fig. 8, and rapidly increases as the parts approach the dotted line position in which they are 15 shown in Fig. 8. This not only constitutes an extremely simple construction for producing an accelerated movement, but also permits the application of the power that rocks the shaft 34 in a direction that is most 20 effective to pull the shaft in the desired direction, as will more fully appear.

The means for imparting the desired rocking movement to the crank shaft 34 might be variously constructed, and is shown in 25 Figs. 1 and 2 as comprising an operating cable 40 one end of which is secured to a bolt 41 that may be adjustably secured to a cross beam 42 of the supporting casing by a nut 43 engaging a threaded end of the bolt. 30 An intermediate portion of the cable 40 is looped about a grooved sheave 44 mounted upon an eccentric 45, which eccentric is rigidly secured to an operating shaft 46. This shaft is journaled in the bearing 35 brackets 47 and may be driven by a pulley (not shown). The other end of the cable 40 is secured to the crank shaft 34, and to this end, in the construction shown, the crank shaft is provided with a lever or arm 48 the 40 inner end of which may embrace the shaft 34 and the outer end of which is provided with a yoke 49 to which the end of the cable is secured, the yoke being connected to the outer end of the lever by a pin 50. The arrangement just described is such that as the 45 power shaft 46 rotates, the eccentric 45 on this shaft rotates within the sheave 44 and moves the latter bodily toward and from the crank shaft 34. This serves to alternately 50 tension and slack off the cable 40, to thereby impart the desired rocking movement to the crank shaft 34. A spring 51 is preferably provided having one end anchored to the supporting casing at 52 and the other end 55 secured to the lever 48, so that this spring will continuously urge the crank shaft in a direction to maintain the cable 40 taut. The spring 51 serves also to pull the crank shaft 34 away from its dead center position with 60 respect to the cable 28.

The nature of the accelerated movement imparted to the frame 10 may be easily varied as desired by changing the position of the arc thru which the crank shaft 34 rocks. This may be best illustrated by ref-

erence to Fig. 8, wherein the operating parts just described are shown on a much larger scale. The angle thru which the crank shaft 34 rocks obviously may be made as small, or as great as desired, depending upon the construction of the operating eccentric 45 or other operating means. Let it be assumed that the angle thru which the crank shaft 34 is moved equals an angle of 35° and that the path of this movement lies between the line 70 indicated by zero of Fig. 8 and that indicated by 35, wherein the zero line indicates the position occupied by the crank shaft when it imparts its maximum take-up movement to the cable 28. It will be apparent 75 that by increasing the length of the power operating cable 40 the angle thru which the crank shaft rocks may be shifted in a clockwise direction, viewing Fig. 8, so that it will move back and forth thru some other angle 80 such as that defined by the lines 10° and 45°. In this case the movement imparted to the frame 10 will be more energetic than in the case where the angle of movement is confined between the lines 0° and 35°. 85

The length of the operating cable 40 may be varied by adjusting the nut 43, or if it is desired to make a substantial change in the position of the operating parts, then the angular position of the lever 48 may be 90 changed relatively to the side arm 53 of the crank shaft by removing the bolts 54 from the position in which they are shown in Fig. 4 and inserting them in the holes 55 to thereby effect an angular adjustment between the 95 levers 48 and 53. 100

From the foregoing description of the novel movement forming the subject matter of the present invention and means described for effecting the same, it will be seen that the sheave 33 moves from the position shown in full lines in Fig. 8 to the position shown in dotted lines in this figure under the action of the springs 22 and 51, thus slackening off the cable 28 to permit the frame 10 to move in a right-hand direction. It will also be seen that the movement of the sheave 33 in the opposite direction, to take up the cable 28, is effected by exerting a pull on the power operating cable 40 that pulls the crank shaft 105 in a contra-clockwise direction, this being effected by the rotating eccentric 45 acting upon the sheave 44. As a result of this construction an extremely small amount of power utilized to rotate the eccentric shaft 46 will serve to impart the desired progressive movement to the frame 10, and, since the parts are extremely simple in construction, they are inexpensive to manufacture 110 and are strong and durable and are not likely to be injured by dust or dirt to which they may be subjected in operating screens and concentrator decks. 115

In the modified construction shown in Fig. 5 the construction and operation is substan- 120 125 130

4

tially the same as that shown in Figs. 1 and 2, except that a pitman rod 56 is employed to actuate the crank shaft 34 in place of the operating cable 40. This pitman rod may be actuated by an eccentric 57 on the power operated shaft 58. In this modified construction it will be necessary to impart a greater throw to the eccentric 57 than in the construction shown in Figs. 1 and 2 because when a cable is employed as in Figs. 1 and 2, having one end anchored and the other end connected to the crank shaft, the movement imparted to the free end of the cable 40 will be substantially four times as great as the displacement of the eccentric from the central axis of the power shaft, whereas in Fig. 5 employing the pitman the movement imparted to the crank shaft 34 will be approximately twice the displacement of the eccentric from the axis of its operating shaft.

In the modified construction shown in Fig. 6, the construction and operation is substantially the same as that shown in Figs. 1 and 2 except that the operating sheave, instead of being mounted upon the wrist pin of the crank shaft, as in Figs. 1 to 5 inclusive, is mounted upon a relatively large eccentric 59 secured to the shaft 60, and about this eccentric is mounted a sheave 61, anti-friction bearings being provided between the eccentric and sheave. Rocking movement is imparted to the shaft 60 and its eccentric 59 by a crank arm 62 to which the cable 40 is secured by the yoke 49.

When the frame 10 is supported for back and forth movement by swinging arms 15, as shown in Figs. 1 and 2, it may be desirable to vary the connection between the operating cables 18 and 28 and the frame 10, to thereby vary the upthrow movement imparted to this frame by the arms 15. The rods 19 and 29 secured to the cables 18 and 28 respectively are therefore shown as extending thru the sleeves or brackets 63 which are rigidly secured to the transversely extending beams 64 of the frame 10, and these rods may be adjusted lengthwise thru the sleeves 63 by adjusting the nuts 65. The adjacent ends of the rods 19 and 29 are preferably connected by the threaded hand buckle 66, this construction being desirable in order that the pull of one cable may be directly transmitted to the other thru the hand buckle 66.

It will be apparent from the foregoing that the nature of the accelerated movement imparted to the frame 10 may be readily varied as desired by increasing or decreasing the length of the operating cable 40 to thereby vary the position of the angle through which the crank arm rocks. It will also be apparent that when the frame 10 has reached the end of its stroke in a right-hand direction it is quickly pulled in the opposite direction by the power actuated means, thus im-

parting a progressive movement in a right-hand direction to the materials being treated. The movement of the frame 10 in a left-hand direction under the action of the power operating means gradually decreases in speed as the crank shaft 34 approaches its position of maximum take-up movement shown in full lines in Fig. 8.

What is claimed is:

1. In combination with a frame supported for back and forth movement, operating means for imparting a progressive, vibratory movement to the frame, comprising a sheave, a cable looped about the sheave and having one end anchored and its other end secured to said frame, a rocking support for said sheave constructed to move the sheave bodily to and from a dead centre position with respect to said cable, and means for rocking said support thru a limited angle lying near said dead centre position.

2. In combination with a frame supported for back and forth movement, operating means for the frame, comprising a sheave, a cable looped about the sheave and having one end anchored and its other end secured to the frame, a crank shaft having an off-set portion upon which the sheave is journaled, and means for rocking the crank shaft thru a limited angle to tension and slack-off the cable.

3. In combination with a frame supported for back and forth movement, operating means for imparting a progressive vibratory movement to the frame, comprising a rocking member having a cable actuating portion off-set from the axis about which the rocking member swings, a cable looped about said off-set portion and having one end anchored and its other end secured to the frame, and means for rocking said member to move its off-set portion back and forth through a small angle lying adjacent the dead centre position of the off-set portion with respect to said cable to thereby tension and slack off the cable.

4. In combination with a frame supported for back and forth movement, operating means for the frame, comprising a rocking member having a cable actuating portion off-set from the axis about which the rocking member swings, a cable extending from the frame to the off-set portion, means for rocking said member to move its off-set portion back and forth through a small angle lying adjacent the dead centre position of the off-set portion with respect to said cable, and an adjustable connection between the rocking member and operating means to vary the position of the arc thru which the member rocks with respect to said dead centre position.

5. In combination with a frame supported for back and forth movement, operating means for the frame, comprising a sheave,

a cable having an intermediate portion bent about the sheave and having one end secured to the frame and the other end anchored, a rocking member having an off-set portion upon which the sheave is mounted and which normally extends from the axis of the rocking member in the direction of the cable take-up movement so that a line passing through said axis and centrally through said off-set portion lies approximately parallel to the portion of the cable extending from the off-set portion towards said frame, and means for rocking said member through a limited angle toward and from said normal position.

6. In combination with a frame supported for back and forth movement, operating means for imparting a progressive vibratory movement to the frame, comprising a rocking member having a cable actuating portion off-set from the axis about which the rocking member rotates, a cable looped about said off-set portion and having one end anchored and its other end secured to said frame and arranged so that the strands of the cable extending from the opposite sides of the off-set portion lie in substantially parallel relation to thereby impart a movement to the frame that is equal to twice the movement of the cable actuating means in the cable tensioning direction, and means for rocking said member through a limited angle about said axis to and from the position of maximum cable take-up movement.

35 7. In combination with a frame supported for back and forth movement, operating means for the frame, comprising a rocking member having a cable actuating portion off-set from the axis about which the rocking member rotates, a sheave supported by said off-set portion, a cable looped about said sheave and having one end anchored and its other end secured to said frame and arranged so that the strands of the cable

at the opposite sides of the sheave lie approximately parallel to each other to thereby impart a movement to the frame that is equal to twice the movement of the cable actuating means in the cable tensioning direction, and means for rocking said member. 45 50

8. In combination with a frame supported for back and forth movement, operating means for the frame, comprising a rocking member having a cable actuating portion off-set from the axis about which the rocking member rotates, a cable extending from the frame to the off-set portion, and means for rocking said member to actuate it, including a power driven eccentric, and a second cable anchored at one end and having 60 its other end secured to the rocking member and having an intermediate portion looped about said eccentric to cause the latter to impart to the active end of said second cable a movement that is double the movement of 65 the eccentric in the cable tightening direction.

9. In combination with a frame supported for back and forth movement, operating means for imparting a progressive vibratory 70 movement to the frame, comprising a rocking shaft having a pair of arms extending laterally from the shaft in spaced relation to each other and having a cable actuating element pivotally mounted between them 75 near their outer ends, a cable extending from the frame to said actuating element and arranged to be actuated with a variable speed movement as said arms move through a small angle to and from the dead centre 80 position of the arms with respect to said cable, and means for pulling the rocking arms from a slightly inclined position to said dead centre position to impart a rapidly decreasing speed to the cable. 85

In testimony whereof, I have signed my name to this specification.

ALBERT H. STEBBINS.
